UNITED STATES PATENT OFFICE

CHARLES W. FARRINGTON, OF BEDFORD, MASSACHUSETTS

TUBE-SOCKET CLEANER

Application filed July 18, 1928. Serial No. 293,762.

This invention relates to radio apparatus and particularly to receiving sets and aims to provide a novel and improved device for removing the corrosion, dust and any deposit, 5 the result of electrical action from the contacts in the tube sockets.

In the drawing of one embodiment of my invention selected for illustration and description,

10 Fig. 1 is a side elevation of my novel device;

Fig. 2, a vertical section thereof;

Fig. 3, a cross-section on the line 3—3, Fig. 2;

15 Fig. 4, a vertical section through one form of socket usually termed the U V type of socket showing my device positioned therein for use;

Fig. 5, a similar view of the device in another type of socket known as the U X type; 20 and

Fig. 6, a modified form of the polishing spindle.

My novel cleaning device, as illustrated, Fig. 1, comprises a handle 1 of any convenient 25 and suitable outline and material as wood, drilled lengthwise, Fig. 2, to receive a shaft 2, and high enough to permit its convenient use above the top of the shield that some receiving sets are provided with.

30 On the upper end the shaft, Fig. 2, is provided with a preferably metal collar 3 resting on a washer 4 and a head 5 is secured to the shaft 2 as by a set screw 6 through a metal bushing 7.

35 The lower end of the shaft 2 carries, Fig. 3, a pinion 8 preferably of fiber or other suitable insulation which meshes with and rotates pinions 9, 10, 11, 12.

40 The lower end of the handle 1 may have formed therein a chamber α as, for instance, it may be received within a head or shell 13 of any suitable material as hard rubber, fiber, etc., abutting against a flange 14.

45 Each pinion 9, 10, 11, 12 carries an elongated depending spindle or shaft 15 which turns in a bearing 16 in the bottom wall 17 of the shell 13 while the lower end of the shaft 2 is reduced and rests in a slot 18 in the wall 17. The spindles 15 are of such material 50 that they may be provided with an abrasive

surface 19, like a file, or, Fig. 6, they may be provided with a coat of carborundum, emery, or other abrasive or cleaning material. Or, if preferred, the spindles may be smooth and a polishing powder used there- 55 with.

As is well known, the metal contacts in radio equipment after a while become corroded and foul with dust so that the efficiency of the instrument is impaired.

To clean the contacts 21 in the U V type of socket, the lower end of the handle 13 is inserted in the socket 23 until the flange 14 rests upon the top of the socket and turned until the pin 25 engages the usual locking slot 60 in the socket, not shown, when the lower ends of the polishing members 19 rest upon the contacts 21 without bending them downward excessively. The head 5 is then rotated, thus rotating each of the spindles 9 to 12 and 65 cleaning that part of the surface of the contact member 21 where the pins on the tubes usually rest.

In the case of a U X socket where the contacts are on the side of the pin openings as in 75 Fig. 5, the members 19 will clean them on the side or edge adjacent the pins.

Naturally the spindles will be of such number and size or various sizes and arrangement as are necessary for the different types of 80 sockets in general use.

Obviously many changes may be made in the details of construction all within the spirit of my invention and the scope of the 85 claims.

My novel device above described will clean and polish the contacts thoroughly and quickly. The device is compact, not expensive and may readily be carried in a kit of tools, if desired.

90 This invention is not restricted to the precise embodiment thereof described and illustrated, but is more particularly pointed out in the following claims.

Claims:

1. A tube socket contact cleaner comprising a handle carrying a movable driving member and cooperating socket entering movable cleaning members mounted on the handle for said first named member with pol- 100

ishing areas to engage said contacts on the sides and end thereof.

2. A tube socket contact cleaner comprising a handle, a shaft therein with a head, a driving pinion on the shaft, a plurality of pinions meshing with the driven pinion and each carrying a polishing spindle positioned to engage a contact.

3. A tube socket contact cleaner comprising a handle, a shaft therethrough with a head, a driving pinion on the shaft, driven pinions meshing with the driving pinion and carrying elongated spindles with polishing surfaces thereon constructed to extend through the bottom of the socket and engage the contacts.

4. A tube socket contact cleaner comprising a handle, a rotatable driving member therein with a head, a driving pinion on the said member, a plurality of cooperating driven elements for said driving pinion with abrasive elements thereon to clean the pin contacts.

5. A tube socket contact cleaner comprising a handle, a shaft therein with a rotating head, a chamber on the lower end of the handle with a plurality of pinions enclosed therein operatively connected to the shaft each carrying a cleaning member constructed to engage and polish a tube socket contact.

6. A tube socket contact cleaner comprising a handle with a chamber on one end constructed to overlie the tube support, polishing members mounted in the chamber wall and constructed to extend through the socket bottom and engage the contacts to clean them, and means to rotate from the handle top the polishing members.

In testimony whereof, I have signed my name to this specification.

CHARLES W. FARRINGTON.
